18 Claims. (Cl. 139—126)

This invention relates to looms of a type in which threads from different sources are carried in opposite directions through successive sheds by a pilot or weft carrier which is repeatedly projected across a loom. In the loom of the present invention all of the operations which are required for the placing of filling threads or wefts in a fabric are controlled by mechanisms which are mounted on a laybeam and are synchronized with respect to the reciprocating movements of the laybeam. A complete mechanism is mounted upon each end of the laybeam. These mechanisms are mirror likenesses of one another and function similarly in different cycles of the loom with one of the mechanisms serving to insert a filling thread from one side of the loom and the other mechanism serving to insert a filling thread from another source at the other side of the loom.

Among the objects of the invention is to provide improved projecting mechanisms operational at high speeds to effect the insertion and the complete placement of weft threads, including the release of a thread from a pilot received at one end of the laybeam, the pick-up of another thread by a pilot on the fly from the same end of the laybeam, the automatic control of a thread-braking or tensioning device to release restraint on a thread during the flight of a pilot from a projecting mechanism and to apply restraint to the free running of the thread just before the pilot is received at the other end of the laybeam, the holding and cutting of an inserted thread between a selvage edge and the projecting mechanism from which it has been carried across the loom, and the positioning and holding of a cut end of the thread for pick-up by the pilot when the pilot is again projected from the same projecting mechanism.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawing.

In the drawing:

Fig. 1 is a back elevation of the left hand projecting mechanism showing the various elements in position as the lay is moving backwardly at the approximate moment of projection of a pilot therefrom;

Fig. 2 is a plan of the projecting mechanism in the condition shown in Fig. 1;

Fig. 3 is a front elevation of the projecting mechanism in the condition shown in Fig. 1;

Fig. 4 is an elevation of the inboard end of the left hand projector as viewed from the center of the loom;

Fig. 5 is an elevation of the back of the projector with the various elements disposed in positions in which they are when the lay is at the front-center position correspondingly only to the positions of the crank at 0° or at 720°;

Fig. 6 is an elevation of the back of the projector with the various elements disposed in positions in which they

2

are when the lay is at the back-center position corresponding only to the position of the crank at 180°;

Fig. 7 is an enlarged vertical section on the longitudinal axis of the inboard end of the projecting mechanism with the positions of the various elements corresponding to their positions as illustrated in Fig. 1;

Fig. 8 is an elevation of the inboard end of the projecting mechanism as viewed from the left of Fig. 7;

Fig. 9 is a vertical section on line 9—9 of Fig. 7;

Fig. 10 is a sectional view along stepped horizontal planes generally indicated by 10—10 in Fig. 7;

Fig. 11 is a horizontal section on line 11—11 of Fig. 7;

Fig. 12 is a detail illustrating the open position of the shears;

Fig. 13 illustrates the releasing action which frees a filling thread from a pilot that has come to the projecting mechanism from the other side of the loom;

Fig. 14 is an elevational view of the mechanism for controlling the operation of the thread-releasing device as seen from the front of the projecting mechanism with the lay at front-center (0° or 720°);

Fig. 15 is illustrative of the position of the controlling mechanism shown in Fig. 14 with the lay at back-center (180°);

Fig. 16 is a vertical cross-sectional view through the cocking fork on line 16—16 of Fig. 1.

In the following description and in the claims, various details will be identified by specific names for convenience, but they are intended to be as generic in their application as the art will permit.

In the drawing accompanying and forming part of this specification, certain specific disclosure of the invention is made for purposes of explanation, but it will be understood that the details may be modified in various respects without departing from the broad aspect of the invention.

Referring first to Fig. 4, the laybeam 10 is attached by bolts 11 to a pair of lay swords, the left hand one of which is illustrated at 12. The lay swords are pivotally mounted on a shaft 13 which is supported in brackets, such as the bracket 14 which is secured to the left hand loom side 15. The laybeam is reciprocated by the simultaneous movements of the lay swords. Each sword is reciprocated by a connecting rod 16 having its rear end pivotally connected to a crank 17 which is carried by the crankshaft 18 of the loom. The crankshaft 18 is mounted in bearings 19, one at either side of the loom.

A reed 20 is clamped to the swords and the laybeam. A plurality of pilot guide plates 21 are mounted spacially in assembled relation on a bar 22 which is clamped to the laybeam. These guide plates have notches which, together with the reed, define a raceway across the front of the reed for a pilot 23. The guide plates 21 are moved from and to below the fell of the fabric and enter between the warps as the laybeam is reciprocated. 24 is a conventional temple at the left edge of a fabric being woven.

Two cycles of the loom, or two revolutions of the crankshaft are required to complete all of the operations of a single projecting mechanism. Since all of the operations at one side of the loom are duplicated at the other side of the loom at intervals of 360° by the respective projecting mechanisms, a full disclosure of the invention is attainable from a description of either one of the projecting mechanisms. The following description is with respect to the mechanism at the left side of the loom and its operation during the movement of the lay from front-center (0°) to back-center (180°) and then forwardly to front-center (360°) during a first cycle which is designated herein for convenience as an odd-numbered cycle, and then to back-center (540°) and to front-center (720°) during a second or an even-numbered cycle as the crankshaft makes two revolutions.

Referring to Figs. 1, 2 and 3, the projecting mechanism

includes a body member 25 having legs 26 and 27 bolted to the laybeam 10 by any suitable means such as bolts 28, 29. The inboard end of the body member 25 provides a box 30 into which a pilot is received and from which it is projected. All of the operations of the projecting mechanism are effected through the medium of a movable member in the form of a rod 31 which is carried by the laybeam. The rod 31 is slidably mounted in guiding bores through the legs 26 and 27 of the body member. The slide rod 31 moves inwardly (as indicated by the arrows 32, Figs. 1 and 3), or towards the inboard end of the projecting device, as the lay moves backwardly, and outwardly or towards the outboard end of the projecting device and of the laybeam as the lay moves forwardly in the return stroke of each revolution of the crank 17. The slide rod 31 is shown in its most outboard position in Fig. 5 when the crank is at front-center, and in its most inboard position in Fig. 6 when the crank is at back-center.

The slide rod 31 carries a block 33 which is pinned to it by a screw 34. A pair of lugs 35, Figs. 2 and 3, extend from the front side of the block and are pivotally connected to an adjustable link 36 by a pin 37. The other end of the link 36 is pivotally connected to an arm 38 which is fastened to the upper end of a shaft 39 journaled in a bracket 40 mounted on the laybeam and secured thereto by bolts 41. The lower end of the shaft 39 has fixed thereto a lever arm 42 whose free end is pivotally connected to a link 43 which is swivelled to a stationary post 44, Fig. 4. The post is attached to and stands upwardly from a plate 45 bolted to the bracket 14. The bracket 14 is solidly attached to the loom-side 15 by bolts 46. The articulated arrangement is such that as the lay moves backwardly, the slide rod 31 moves toward the inboard end of the projecting device and as the laybeam moves forwardly the slide rod moves toward the outboard end of the projecting device.

The projecting device is viewed from the back of the loom in Figs. 1, 5 and 6. In Fig. 5, the parts of the projecting device are illustrated at the beginning of the first cycle or at zero degrees, and in Fig. 6 the parts are illustrated in their positions when the lay is at back-center or at 180 degrees of the first cycle. As illustrated in Fig. 1, the various parts are shown with the crank at about 85° or at just before the projection of the pilot. The screw 34 carried by the block 33 and pinned to the slide rod 31 passes through a hole in a link 50 and carries the link with it as the slide rod is reciprocated.

A tripping slide member 51 is sandwiched between the link 50 and the rear face of the block 33. The slide member 51 has a tripping cam 52 projecting laterally therefrom to engage and operate an arm 54 of a tripping lever by which a series of operations is initiated, including the projection of a pilot, as will appear more fully hereinafter. The slide member 51 has a laterally extending ear 55 which has an opening surrounding the slide rod 31 and providing an edge which serves as a support and pivot for the inboard end of the slide member. The outboard end of the slide member 51 has a cam slot 56 which is engaged by a roller 57 on the stem of the screw 34. This cam slot is so shaped as to move the outboard end of the slide member 51 upwardly with respect to the screw 34 to place the cam 52 in position for actuating the lever 54 and to move the cam downwardly and into position for avoiding contact with the lever 54, under conditions which will be explained in more detail hereinafter. During the upward and downward movements of the slide member 51 and the cam 52, the slide member pivots on a bearing provided between flange 55 and the slide rod.

A post 58 is fixed to and extends laterally from the slide member 51 and passes through a slot 59 in the link 50 whereby movement of the link may continue after the longitudinal movement of the slide member 51 has been interrupted in either direction. The slide member 75

51 is made to travel longitudinally with the link 50 through limited distances by frictional engagement between the link and the slide member whenever the longitudinal motion of the slide member is not interrupted.

5 The frictional force is established by washers on the post 58, including a spring washer 60, which are disposed between the nut 61 and the link 50. The inboard movement of the slide member 51 is limited by a fixed stop 62 which is secured to the underside of the pilot box by a pair of bolts 63. The outboard movement of the slide member 51 is limited by a pivoted stop 64 whenever a pilot is contained in the pilot box and the lay is moving toward front-center. This stopping action normally occurs as the slide rod 31 and the slide member 51 are moving outwardly during the second cycle of the loom after the pilot has been received from the right side of the loom. The pivoted stop 64 is pivoted on a pin 65 and it is biased upwardly out of the path of the flange 55 by a spring 66 when the pilot 23 is not in position in the pilot box. A spring member 68 (Fig. 7) is pivotally mounted on a pin 69 and is in constant engagement with the pivoted stop 64. When a pilot is present in the pilot box the spring 68 is depressed by the pilot and forces the stop downwardly against the action of the spring 66 and into the path of travel of the flange 55. The pivoted stop 64 is never effective to stop an inward movement of the slide member 51.

20 The striker element or plunger 70 by which the pilot 23 is projected is mounted for sliding movement within 30 a bore in the body member 25. The inboard end of the plunger 70 slides through a sleeve 72, Fig. 11, and the outboard end of the plunger is provided with a cylindrical head 73 which is guided in a sleeve 74 contained in the bore. The head carries a pin 75 extending in 35 diametrically opposite directions through slots 76 and 77 at the back and front, respectively, of the body member 25.

35 The pin 75 is engaged by the fingers 78 and 79 (Figs. 1, 3 and 16) of a cocking fork 80 whenever the plunger is to be restored to cocked position. A yieldable check-plate 81, secured to the front side of the projector mechanism by screws 82, engages one end of the pin 75 and holds the plunger in retracted position until it is propelled therefrom by a reduction lever 83. The inward or firing motion of the striker element or plunger 70 is arrested by a bumper cap 84 encircling the plunger and covering one end of a composition rubber tube 85 (Fig. 11) whose other end is buttressed by a ring 86.

40 The reduction lever 83 is pivotally mounted by trunnions 88 journaled in a pair of standards 89, 90, extending upwardly from a cap piece 91 which is secured to the body member 25 by any suitable means, such as bolts 92. The lever is actuated by energy stored in a spring 93 which is supported at one end by a cap 94 pivotally connected to the lever 83 by a shaft 95 on the lever. The spring is compressed between the cap 94 and a cap 96 at one end of a threaded stem 97 which is fastened to a fixed support 98 by a pair of nuts 99, 100.

45 The reduction lever 83 is held in its retracted position against the tension in the spring 93 by a catch 101 having a finger 102 adapted to engage a lip 103 at the free end of the lever. The residual energy of the spring 93 following the acceleration and projection of a pilot is absorbed by a cushioning device 104. As illustrated in Fig. 6, the cushioning device 104 includes a hollow member 105 having a cylindrical chamber containing a resilient tube 106 of a rubber composition with a disk 107 at one end and an adapter 108 at its other end for seating a steel cap 109. A set position of the disk 107 is determined by an adjustable screw 110 and a lock nut 111. Member 105 is supported by a bracket 112 which is fastened to the cap 91 by two of the bolts 92.

The cocking mechanism

50 The plunger 70 and the lever 83 are retracted together

to cocked position as the slide rod 31 moves outwardly during the forward movement of the lay immediately following the backward movement of the lay (Fig. 1) during which the lever 83 is released for propelling a pilot. The plunger 70 and the lever 83 are retracted by the U-shaped cocking fork 80 which is carried by the block 33 on the slide rod 31 (Figs. 1, 3, 6 and 16). The legs of the cocking fork terminate in the fingers 78 and 79, respectively, and they are guided for vertical movement by guides 117 in the back of the block and by guides 118 at the front of the block. The respective legs have slots 119, 120 through which pins 121, 122 extend from the block 33. The cocking fork is normally urged to its lowermost position by a spring 114, and in this position (Figs. 1, 3, 5 and 16) the fingers 78 and 79 are below the level of travel of the pin 75 on the plunger head 73. The cocking fork remains in its lowermost position except when it is supported on an elevator 123 during the latter part of the inward motion of the slide rod 31 or during the outward motion of the slide rods whenever the fingers 78 and 79 engage the pin 75 to retract the plunger.

The elevator 123 is slidably supported in a guide 124 for movement parallel to the direction of movement of the slide rod 31, and its inward movement is yieldably resisted by a spring 125. As the slide rod moves inwardly (Fig. 1), the cocking fork 80 comes into contact with the cam surface 126 and is raised onto the elevator 123 as the elevator slides a limited distance against the action of the spring 125.

During the beginning of the outward movement of the slide rod the fingers 78 and 79 engage the ends of the pin 75 on the plunger 70 and the elevator 123 returns to its starting or idle position. The friction on the fork 80 due to the reaction of the projection spring 93 is sufficient to hold the fork in engagement with the pin 75 until the reduction lever 83 is engaged and latched in cocked position by the catch 101.

As the plunger 70 moves outwardly slightly beyond its cocked position, the free end 103 of the lever 83 engages a projection 127 on the catch 101 and rocks the catch and a latch member 147 counterclockwise to latched position (Fig. 5). The finger 102 on the catch engages the lip 103 and holds the lever 83 retracted or in cocked position. As will appear more fully hereafter, the catch 101 and the latch member 147 together serve as a detent device which is restrained against release to the action of a spring 146 by a trigger member 144. The head 73 of the plunger is held in contact with the lever 83 by the check plate 81 on the front side of the projector body 25, Fig. 3. As the pressure from the spring 93 is relieved from the cocking fork 80 the fork drops to below the level of the path of travel of the pin 75.

The projection and retraction of the plunger occurs during an odd cycle of the loom during which the slide rod 31 moves inwardly and then outwardly. During the next or even cycle the cocking fork 80 is again raised by the elevator 123 during the inward movement of the slide rod, but as the slide rod moves outwardly the cocking fork drops to its lowermost position upon leaving the elevator because the plunger had been retracted during the previous odd cycle and is therefore not in position for the fingers 78 and 79 to engage the pin 75. The fork remains lowered when the plunger is next released to propel the pilot during the backward movement of the lay in the following odd cycle of the loom.

The cocking and tripping actions of the slide rod 31 and of the tripping slide 51 are carried out in a manner substantially similar to the functioning of corresponding members disclosed in my copending United States application Serial No. 588,152, filed May 29, 1956, and granted March 15, 1960, as Patent No. 2,928,428.

The tripping mechanism

As shown in Figs. 7, 10 and 11, the pilot 23 is in the pilot box in home position and the various elements of

the projecting mechanism are disposed in the positions they assume immediately preceding the projection of the pilot from the box. These positions correspond with the instantaneous positions of the elements as illustrated in Fig. 1. Referring first to Fig. 11, one end of the pilot is received in a ring 129 of wear-resisting material which, together with a cushion member 130, is contained in a cylindrical bumper cup 131. The rebound of the pilot upon arriving from the other side of the loom is prevented by a latch 132 which is pivotally mounted at 133 and is normally pressed by a spring 134 to extend into the pilot box and into the path of the oncoming pilot. After the latch has been brushed aside by the pilot the spring 134 pivots the latch into engagement with the shoulder of a recess 135 in the side of the pilot and the latch prevents the pilot from rebounding from the box.

As shown in Fig. 11, the latch 132 has been disengaged from the pilot and the pilot is free for projection. The disengagement has been effected by the camming action of a latch cam 136. The latch cam is in the form of an arm which depends from the hub of a lever 137 as best shown in Figs. 1 and 9. The hub of lever 137 is keyed to a rockshaft 138 which is journaled in a pair of standards 139, 140, rising from the gib 141 overlying the pilot chamber in the pilot box.

The lever 137 is pivotally connected at 142 to an adjustable link 143 whose outboard end is pivotally connected to a trigger member 144 which is loose on a shaft 145 and is biased to turn counterclockwise (Fig. 1) by a spring 146 connecting between the trigger member and a latch member 147. The latch member is secured to a shaft 148 to which the catch 101 is also secured. The cocked position of the trigger member 144 is as illustrated in Fig. 5. At the beginning of an odd cycle with the lay at front-center (Fig. 5), a projection 150 on the latch member 147 is engaged in a notch 151 of the trigger member 144 and the two members are held in engaged relationship by the tension in the spring 146. The trigger member 144 is thereby held in cocked position until it is tripped.

The spring 146 acts to rotate the latch member 147 and the catch 101 clockwise to release the lever 83 and effect a projection of the pilot when the latch member 147 is released from engagement in the notch 151 as the trigger member 144 is rotated clockwise from cocked position (Fig. 5) by an arm 152 and a pin 153 which is carried by the arm and extends into an arcuate slot 154 in the trigger member. The arm 152 and the arm 54 are fast on the shaft 145 and together constitute the tripping lever. The pin and slot connection permits the lever arms 54, 152 to turn counterclockwise (Fig. 1) after the cam 52 has passed by and freed the arm 54. The counterclockwise movement of the shaft 145 effects a braking action on the filling thread as will appear hereinafter.

As previously explained, the plunger 70 and the reduction lever 83 are released to project a pilot when the arm 54 is rotated clockwise by the cam 52 on the slide member 51 as the slide member moves inwardly, Fig. 1, during an odd cycle. The tripped position of the tripping mechanism, including the catch 101, the latch member 147, trigger member 144, and the tripping lever 54, 152, is illustrated in Fig. 6.

The pilot and the filling thread

The pilot is an elongated body member, as best seen in Figs. 7 and 11, having a longitudinal groove 155 extending from end to end in its top side and in which two similar thread grippers are located. These grippers are generally indicated at 156 and 157. The grippers face each other so that either gripper may serve as a trailing gripper to pick up a thread, depending upon the direction of projection of the pilot across the loom. Each gripper includes a hook 158 and a resiliently yieldable plate member 159 which is pivoted at 160 and is

pressed against the lower edge of the hook by a spring 161 to engage a thread between the hook and the plate. As best seen in Fig. 11, the plate member 159 is substantially as wide as the groove 155, and the hook 158 is relatively narrow so as to permit the fingers 162 and 163 of a thread-positioning element 164 (Fig. 7) to pass at either side of the hook as a pilot is projected. The fingers 162 and 163 are moved into the groove 155 to depress a thread into the groove and into position for being picked up by the gripper 157 which is the trailing gripper in respect to the projecting mechanism shown in Fig. 11. The operation and control of thread-positioning element 164 will be explained in more detail hereinafter.

The cycling of the warps is preferably substantially as follows. At the front-center position of the lay of each cycle the shed of warps is fully open and the shed remains open as the crank rotates through 180°. The shed starts to close at back-center and is fully closed when the crank reaches 270°. The warps reverse and the shed opens during the remainder of the cycle as the lay returns to front-center. In the cycling described a filling thread inserted in either direction is bound in the cloth by the changing warps and beat-up before another thread is picked up by the pilot and inserted in the opposite direction.

The thread 167 fed to the left hand projector is supplied from a package 168 and is drawn across the loom by the pilot during each odd cycle. After insertion the tail end of the inserted thread is clamped and cut by a holding and shearing mechanism generally identified as 169. The cut end 170, which is to become the leading end of the next thread to be inserted from the left, is held by the holding and shearing mechanism, as indicated in Fig. 7, while another filling thread is inserted in a shed from the opposite direction as the pilot is returned to the left side of the loom during an even cycle. The end 170 is held until it is picked up by the pilot in the next following odd cycle.

The diagonal disposition of the thread as indicated in Fig. 11 is brought about as the result of the forward and downward movement of the pilot box past and below the fell of the cloth as the lay approaches front-center (360°) towards the end of an odd cycle. As this action occurs the reed meets and advances the weft toward the fell and the connecting length of thread which extends through the box to the weft is displaced crosswise of the box under the fingers 162, 163, of the raised thread positioner 164. The downward movement of the box causes the portion of the thread extending from the weft to move upwardly relatively to the box and into the open jaws of the holding and shearing mechanism 169 which subsequently close on the thread before the lay arrives at front-center at the end of an odd cycle. The holding and shearing mechanism will be described more fully hereinafter.

The cut end 170 is at the leading end of the thread 167 which comes from the supply package 168, and passes through a thread-breaking and tensioning mechanism 171 and a break detector 172 at the front side of the projector (Fig. 3), and then through a plurality of guides such as at 173, 174, 175 and into a slot 176 in the pilot box directly below the gib 141 (Figs. 9 and 11), and across the pilot beneath the fingers 162, 163 of the thread positioner 164 to the holding and shearing mechanism 169 by which the end 170 is held.

Brake mechanism

The braking mechanism 171 or thread-tensioning device and the break detector 172 are mounted on a panel 178 (Figs. 1, 2, 3, 5 and 6) which is bolted to the front side of the projector, Fig. 3. The braking mechanism includes a three-armed lever 179 pivoted on a pin 180. One arm 181 carries a pin 182 which engages and slides in a slot in an arm 183 fastened to the front end of the

shaft 145 to which the arms 54 and 152 are secured at the back of the projector. A spring 184 (Fig. 3) tends to raise the arm 183 and at the same time lower the arm 54 towards a stop 185.

A second arm 186 of the lever 179 carries a pin 187 which is engageable with the free end of a leaf spring 188 whose other end is anchored to a post 189 on the panel 178. The thread 167 extends between the leaf spring 188 and a stud 190 and is adapted to be engaged between the spring and the stud whenever the arm 186 and the pin 187 are lowered from the position shown in Figs. 1 and 3, to the position shown in Figs. 5 and 6. When in lowered position the spring 188 presses the thread against the stud 190 and exerts restraint on the free movement of the thread. The pressure of the spring on the thread and on the stud 190 is adjustable by a screw 191.

The arm 186 is rocked counterclockwise (Fig. 1) to raise the spring from the stud 190 when the arms 54 and 183 are rocked clockwise by the cam 52. This action occurs immediately preceding the projection of a pilot, at which time the thread is relieved of restraint by the spring and stud and is freed to be carried across the loom by the pilot. The timing of the brake is such that it is "on" or applied at all times except from just before the pilot is projected to just before the pilot has arrived in the projector at the other side of the loom.

Automatic stoppage on failure of filling thread

Should the thread fail or break at any time the loom will be stopped by a safety switch 193, Fig. 3. The thread extends through a pair of loops of a wire 194 which is secured to the panel 178 at 195. The looped end 196 of a lever 197 is normally supported by the thread against the action of a spring 198. In this position the lever 197 prevents the switch arm 199 from operating the switch to stop the loom.

The switch arm 199 is mounted on a pivot 200 and is biased into engagement with a stop 201 by a spring 202. The switch arm carries a flexible blade 203 which is adapted to be engaged by a stud 204 on the arm 205 of the lever 179 each time the lever 179 is rocked counterclockwise (Fig. 3) by the spring 184 through the action of arm 183. If the thread is continuous when this action occurs, the blade 203 flexes because the switch arm 199 is prevented from rotating by the lever 197, but if the thread is broken the lever 197 will have been rocked away from the switch arm and the switch arm will operate the switch and stop the loom. It is to be noted that the arm 205 of the lever 179 is in position to tension the spring element 203 whenever the arm 183 is raised and the arm 54 is in its lowermost position against the stop 185 (Figs. 5 and 6).

Positioning of thread for pick-up

The mechanism for depressing a thread into the groove in the top side of the pilot for pickup by a trailing gripper includes the thread-positioning element or depressor 164 (Figs. 7, 8, 9 and 10). The thread-positioner 164 is carried by a hub 207 which is fixed to a shaft 208. The shaft is journaled in a bearing 209 in the standard 139 (Fig. 10) and in bearings 210 and 211 inside of a hollow shaft 212 which is rotatable in a bearing 213 in the standard 140. The hub 207 also carries a finger 214 (Fig. 7) having a surface 215 adapted to be engaged by a cam 216 which is fast to the rockshaft 138. A torsion spring 217 biases the thread-positioning element 164 downwardly (counterclockwise, Fig. 7). The finger 214 contacts the cam 216 when the projecting mechanism is in cocked condition (Fig. 5) and the cam 216 is removed from engagement with the finger 214 during the tripping action of the projecting mechanism (Figs. 1 and 7) as will be explained more fully hereinafter.

The shaft 208 also has fixed to it a finger 218 (Figs. 1, 5 and 6) having a cam surface 219 which cooperates

with a pin 220 on an arm of a bell crank lever 221 (Fig. 1) to effect clockwise rotation of the shaft 208 to raise and hold the thread depressor 164 until the rockshaft 138 and arm 136 re-assume their positions as shown in Fig. 5. The other arm of the bell crank 221 is bolted to a cam member 222 pivotally mounted on a stud shaft 224. A friction spring 225 is located on shaft 224 between a nut 226 and the cam member 222 whereby to prevent inadvertent displacement of the cam member.

The cam member 222 has a depending finger 227 which is adapted to be engaged by a flange 228 on a bar 229 which is fastened on the link 50 in an adjusted position by a pair of bolts 230, and whereby the cam member 222 and the bell crank 221 are rotated clockwise as the slide rod 31 and the link 50 move inwardly during the backward movement of the laybeam in an odd cycle of the loom.

The cam member 222 has a cam surface 231 adapted to be engaged by a pin 232 on the arm 136 to rock the bell crank and the cam member counterclockwise (i.e. from the position shown in Fig. 6 to the position shown in Fig. 5), upon a counterclockwise rotation of the rockshaft 138.

With the laybeam at front-center and the pilot in the projector box, the slide rod 31 is fully outward (Fig. 5) and the thread 167 is disposed diagonally across the pilot, as indicated in Fig. 11. In the fully outward position of the slide rod 31, the trigger member 144, the link 143 and the lever 137 are in their most inward position and the thread-positioner 164 is in raised position above the portion of the thread which extends across the pilot. The high part of the cam 216 is located opposite the surface 215 on the arm 214 and the thread positioner 164 is thereby held in elevated position.

As the slide rod 31 and the slide member 51 move inwardly, the cam 52 engages the lower end of the arm 54 and initiates a clockwise motion of the trigger member 144 and of the rockshaft 138, thus causing the cam 216 to move clockwise from engagement with the arm 214, whereupon the torsion spring 217 rotates the thread-positioner 164 counterclockwise to depress the thread into the groove of the pilot as shown in Fig. 7 so that it may be picked up by the trailing gripper 157, Fig. 11, when the pilot is projected. Upon further movement of the arm 54 as the cam 52 continues to move inwardly (Fig. 1), the trigger member 144 releases the latch member 147, whereupon the lever or reduction arm 83 is released to project the plunger 70 and the pilot.

The pilot picks up the thread which has been depressed and held in the path of the trailing gripper by the thread-positioner 164 and, as the inward movement of the slide rod 31 and of the link 50 continues, the flange 228 which is carried by the link 50 engages the depending finger 227 and rocks the cam member 222 and the bell crank 221 clockwise to the position shown in Fig. 6, whereupon the pin 220 on the bell crank moves onto the high portion of the cam surface 219 on the finger 218 and thereby rocks the shaft 208 clockwise and raises the thread-positioner 164 from the thread which is running through the pilot box as it is drawn across the loom by the pilot.

The thread-positioner 164 can not leave its elevated position in respect to the pilot box before the pin 220 is returned from the high portion to the low portion of the cam surface 219. The pin 220 is returned to the low portion by displacing the bell crank 221 and the cam member 222 counterclockwise (Fig. 6) while the slide rod 31 approaches the end of its outboard travel during an odd cycle and as the trigger member 144 moves counterclockwise to latched or cocked position. On thus moving, the trigger member pushes the link 143 and rocks the rockshaft 138 and the arm 136 counterclockwise. The rotation of the arm 136 causes the pin 232 to cam the cam member 222 to the position shown in Fig. 5.

The new position of the rockshaft 138 and the restored positions of the bell crank 221 and of the cam member 222 remain undisturbed for the ensuing even cycle (360°-720°) during which the raised position of the thread-positioner 164 is maintained by the cam 216 which is located opposite to the surface 215 on the arm 214.

Action of the tripping slide

Before the flange 228 strikes the depending finger 227 the inward movement of the slide 51 is arrested when it comes into engagement with the stop 62 at the underside of the pilot box, but the slide rod 31 and the link 50 continues to move inwardly. On the stopping of the slide, the roller on the screw 34 rides over the hump 234 of the cam slot 56 and momentarily nudges the cam 52 upwardly before it is moved to its lower position (Fig. 6) as the screw 34 is carried along the cam slot 56 by the slide rod 31. The pivoting of the arrested slide member 51 also lowers the post 58 which causes the link 50 to pivot downwardly about the center of the screw 34 to the position shown in Fig. 6 in which the slide member 51 and the cam 52 are in their lowermost position, and the slide rod 31 has reached the end of its inward stroke with the laybeam at back-center or 180°. The slide rod 31 next moves outwardly as the laybeam swings forwardly without any change in the lowered position of the slide member 51 and of the link 50 because the absence of the pilot from the box has permitted the pivoted stop 64 to be raised by the spring 66 from the path of the flange 55. During this outward movement of the slide rod 31, the raised cocking fork 80 engages the pin 75 on the plunger head and retracts the plunger 70 and the reduction arm 83 to cocked position, as explained hereinabove.

During the next even cycle (360°-720°) the pilot is returned to the pilot box from the other side of the loom, and the pivoted stop 64 is lowered by the pilot to extend into the path of the flange 55 on the slide member 51. As the slide rod moves inwardly the slide member 51 and the link 50 remain in lowered position, but as the slide rod 31 moves outwardly, the lowered stop 64 engages the flange 55 and stops the slide member 51 whereupon the continuing outward movement of the slide rod 31 causes the screw 34 and the cam slot 56 to pivot the slide member 51 upwardly and locate the cam 52 and the link 50 in the relative positions illustrated in Fig. 5 preliminarily to the next projection of the pilot in the ensuing odd cycle, as previously explained.

Thread-holding and shearing mechanism

The thread-holding and shearing mechanism 169 (Figs. 4, 7, 8 and 12) comprises a non-rotatable shear blade 235 extending forwardly from a shank 236 fastened to the end of the pilot box by screws 237, a movable shear blade 238 pivotally mounted on a pin 239 and a spring plate 240 which is yieldably pressed against the side of the movable blade remote from the cutting edges of the two shear blades. The movable blade 238 and the spring plate 240 constitute clamping means which engage a thread before it is cut and hold an end of the cut thread until it is picked up by a pilot as will hereinafter appear. The pivot pin 239 has a rivet head at one end and a nut 241 (Fig. 3) on its other end. A spring 242 which is located between the spring plate 240 and the nut 241 frictionally restrains the movable blade from inadvertent rotation. A pin 243, which is staked to the shank 236, and the pin 239 prevent rotation of the spring plate. The spring plate provides an edge 244 which extends beyond the cutting edge of the non-rotatable blade 235 whereby the thread is gripped and held between the movable blade 238 and the spring plate 240 before it is severed. The movable blade carries an arm 245 by which the blade is pivoted about the pin 239.

The arm 245 is intermittently actuated by a yoke 246 (Fig. 5) attached to the rockshaft 138. A fixed guide

247 is provided to limit the overthrow of the movable blade. A finger 248 on the yoke actuates the movable blade to thread-holding and cutting positions and a finger 249 actuates the movable blade to open the shears. The functioning actions of the shearing mechanism are coordinated with the rocking movements of the rockshaft 138 in opposite directions, as controlled from the arm 137, link 143 and the trigger member 144.

Holding and shearing of a thread which has been carried to the right hand projector occurs at the left hand projector during the forward movement of the laybeam in an odd cycle of the loom, and as the laybeam approaches front-center. At this time the laybeam and the pilot boxes are moving in a descending arc, the leading end of the inserted thread is still held by the pilot in the right hand projector and the thread extends from the cloth and through the left hand projector to the supply package 168. As the boxes move forwardly and downwardly below and past the fell of the cloth, the trailing length of the inserted thread which extends from the cloth to the pilot box slips along a guide wire 250 (Fig. 12) into the open jaws of the shears. The guide wire is fastened to the gib 141 by a screw 251. This movement of the thread along the guide wire 250 is due to the relative vertical motion of the fell and the shears caused by the arc traversed by the laybeam as the reed beats a weft into the cloth.

The shears are moved to close by the finger 248 on the yoke 246 as the rockshaft 138 is rocked counterclockwise close to the end of the forward movement of the lay, at which point the shears are forward and level with the fell. The cut end 170 of a subsequently-to-be-inserted weft is held clamped between the spring plate 240 and the blade 238 of the shears and the thread extends from the cut end directly under the gib 141 to the guide pin 175 and out of the box. As previously explained, the rockshaft 138 is rocked counterclockwise (from the position of the rockshaft shown in Fig. 6) as the plunger 70 and the reduction arm 83 are returned to cocked positions as the laybeam swings forwardly during an odd cycle. The shears remain closed and the cut end 170 (Fig. 7) is held between the movable blade 238 and the plate 240 throughout the ensuing even cycle during which the trigger member 144 reposes at rest and no tripping action occurs. The end 170 is held until the thread is picked up and pulled from the plate 240 by the trailing gripper 157 on the pilot when the pilot is projected from the box in the next following odd cycle, as hereinabove explained in relation to the operation of the tripping mechanism and the projection of the pilot.

While the shears start to open just before the pilot is projected or fired, the end 170 is not released before it is picked up by the pilot. As the rockshaft 138 turns clockwise, the lower finger 249 of the yoke 246 moves towards the arm 245 of the movable blade 238, but it does not contact the arm 245 until after the projecting mechanism is tripped.

Following the departure of the pilot from the pilot box, the outboard end of the tripping slide 51 is nudged upwardly to cause upward movement of the cam 52 and additional upward movement of the finger 249. This action brings the finger into contact with the arm 245 and opens the jaws of the shears. The upward nudge of the cam 52 is produced by the hump 234 on the tripping slide 51 as the slide rod 31 and the roller 57 continue to move inwardly after the tripping slide has been stopped by the stationary stop 62. The shears remain open until they are closed toward the end of the same odd cycle.

The release of a weft thread from the pilot

The pilot is received in the left hand pilot box during an even cycle (360°-720°), as related hereinabove, and it becomes necessary to release the thread which has been

carried across the loom (Fig. 13). The release is initiated and completed while the rockshaft 138 and the arm 137 are in the positions illustrated in Fig. 14. The release of the thread is accomplished as the laybeam 5 is moving toward front-center (720°) and the slide rod 31 is moving outwardly.

The thread is released by rocking a gripper-actuating arm 252 counterclockwise, Fig. 7, to engage and press the pivoted plate 159 of the thread-engaging gripper 156 away from the cooperating hook 158 in the manner illustrated in Fig. 13. The arm 252 extends from the hollow shaft 212, Fig. 10, and it is offset at its free end to enable entrance into the groove 155 in the pilot alongside a hook of the gripper. A spring 277 around the hollow shaft 212 biases the arm 252 clockwise (Fig. 7) and holds it elevated except when a thread-releasing action occurs. A double arm 253 is secured to the hollow shaft 212 by a bolt 254. The double arm carries a pin 255 which passes through an elongated slot 256 in a link 257 as best seen in Figs. 14 and 15.

The upper end of link 257 carries a pin 258 to which a pair of springs 259 is attached. The other ends of these springs are engaged to a pair of stirrups 260 which engage the respective ends of the pin 255 whereby the upper end of the elongated slot 256 in the link 257 is yieldably pressed into engagement with the pin 255.

A lifting of the link 257 causes the arms 252 and 253 to rotate clockwise as indicated in Fig. 14. The tension in the springs 259 is sufficient to overcome the torsion spring 277 and cause the arm 252 to effect engagement with and actuation of the gripper plate 159 in the pilot to release the end 261 of a weft as illustrated in Fig. 13. The springs 259 provide a yielding force whereby to assure a full opening of the gripper.

The link 257 is raised to effect the release of the weft end 261 from the gripper whenever its lower end 262 is engaged and lifted by a roller 263 on a cam member 264 but this action occurs only once in two revolutions of the crank, as will presently appear. The cam member 264 is mounted on a pivot shaft 265 and it is biased to return to its lowermost position by a torsion spring 266 having one end attached to a limit stop 267. The cam member 264 is raised against the action of the spring 266 each time its lower end is engaged by a finger 268 which is bolted to the end of the slide rod 31 and extends laterally from the slide rod and across the camming edge 269 of the cam member. The cam member is rocked clockwise (Fig. 3) each time the slide rod 31 moves outwardly.

An arm 270 is fastened to the front end of the rockshaft 138 and a link 271 is pivotally attached to the arm by a pin 272. Link 271 has an elongated slot 273 which is engaged by a pin 274 carried by the lower end of the link 257. A relatively light spring 275 is attached to the pin 274 and to a stud 276 carried by the link 271. The spring 275 biases the pin 274 toward the end of the slot 273 closest to the stud 276, as shown in Figs. 3, 14 and 15.

In Fig. 3, the slide rod 31 is moving inwardly during an odd cycle to effect a projection of the pilot and the rockshaft 138 is close to the limit of its counterclockwise rotation to the position shown in Fig. 15. The rockshaft remains in this position until it is moved to the position shown in Fig. 14 by the link 143 and the arm 137 as the plunger 70 is returned to cocked position towards the end of the odd cycle as the crank moves to front-center at 360°. But before the rockshaft is rocked clockwise from the position shown in Fig. 15, the finger 268 on the outwardly moving slide rod engages and rocks the cam member 264 and raises the roller 263 alongside of the link 257 where it remains as the finger 268 is advanced by the slide rod 31 on to its most outward position. As a consequence of the lifting of the roller 263 alongside of the link 257, the spring 275 is extended when the link 271 and the arm 270 are actuated by the rock-

shaft 138 and an idle movement of the gripper-opening arm 252 is avoided.

As the laybeam moves backwardly from front-center (360°) during the following even cycle, the slide rod 31 moves inwardly and permits the cam member 264 to lower, whereupon the spring 275 swings the link 257 clockwise as the pin 274 on the link is brought up against the left end of the slot 273 in the link 271.

Weft thread release action

As previously explained, the positions of the trigger member 144, the link 143, the arm 137 and the rockshaft 138 remain unchanged throughout an even cycle (360°-720°) and until a projection of the pilot is initiated in the next following odd cycle. In this unchanged position of the rockshaft 138, the arm 270 is disposed in the position shown in Fig. 14, so that as the laybeam moves toward front-center (720°) and the slide rod moves outwardly, the lower end of the link 257 is disposed directly above the roller 263. Towards the latter part of the outward movement of the slide rod 31 the finger 268 raises the cam member 264 and the roller 263 raises the link 257. The link pivots the arm 253 and the gripper-actuating arm 252 clockwise. The arm 252 thereupon engages and opens the gripper 156 to release a thread therefrom as indicated in Fig. 13.

The gripper actuator 252 remains in engagement with the pivoted plate of the gripper as the lay reverses at front-center and until shortly after the beginning of the next odd cycle when the finger 268 moves from under the cam member 264. As soon as the restraining effect of the finger 268 on the cam member 264 is relieved, the weight of the links 257 and 271 and the torsion spring 277 on the hollow shaft 211 raise the gripper-actuating arm 252 to above the pilot. The arm 252 is raised from the gripper in advance of the projection of the pilot from the pilot box.

Upon release of the pressure of the spring-pressed gripper plate 159 on the weft end 261 the end is blown beyond the gripper plate towards the shank of the gripper hook 158 by a jet of air from a conduit 278, Fig. 10, so that the weft end may run freely from the hook as the laybeam and the pilot box move with respect to the fell of the cloth.

The operation of the apparatus will be apparent to those skilled in the art in view of the foregoing disclosure. The principle of the invention and the apparatus which is now considered to represent the best embodiment thereof have been described in accordance with the provisions of the patent statutes, but it is intended that the apparatus disclosed be illustrative only in that the invention is susceptible of embodiment in other forms. While the apparatus is designed to use the various features and elements in the combinations and relationships described, some of these may be altered and others omitted without interfering with the more general results outlined, and the invention, within the scope of the following claims.

What is claimed is:

1. In a loom having mechanism for reciprocating a laybeam, the combination comprising a laybeam, a pilot-projecting device, said device including a box for receiving a pilot and means for projecting a pilot from said box, means for releasing a thread from thread-gripping means on a pilot in said box, means for controlling the operation of said pilot-projecting means and of said thread-releasing means, said controlling means including a slide rod carrying a member adapted to actuate said pilot-projecting means to effect a projection of a pilot from said box as said slide rod moves in one direction and an element adapted to actuate said thread-releasing means as said slide rod moves in the reverse direction, means for avoiding actuation of said thread-releasing means by said element during every other reverse movement of said slide rod, and means for reciprocating said

slide rod in unison with the reciprocating movements of said laybeam.

2. In a loom having mechanism for reciprocating a laybeam, the combination comprising a laybeam, a pilot-projecting device, said device including a box for receiving a pilot and means for projecting a pilot from said box, means for releasing a thread from thread-gripping means on a pilot in said box, means for operating said pilot-projecting device to project a pilot from said box, said operating means including a trigger member, means for controlling the operation of said operating means and of said thread-releasing means, said controlling means including a slide rod carrying a member adapted to actuate said operating means and trip said trigger member to effect a projection of a pilot as said slide rod moves in one direction and an element adapted to actuate said thread-releasing means as said slide rod moves in the reverse direction, means controlled by said trigger member for preventing actuation of said thread-releasing means by said element during every other reverse movement of said slide rod, and means for reciprocating said slide rod in unison with the reciprocating movements of said laybeam.

3. In a loom having mechanism for reciprocating a laybeam, the combination comprising a laybeam, a pilot box adapted to receive a pilot having releasable thread-gripping means, means for operating said thread-gripping means to release a thread from the pilot, means for projecting the pilot from said box, means for actuating said pilot-projecting means, said actuating means including a trigger member, a slide rod and a cam adapted to move said trigger member from a stationary holding position of the trigger member to a released position to effect a projection of said pilot as said slide rod moves inwardly during an odd cycle of the loom, means for restoring said trigger member to holding position as said laybeam moves forwardly during said odd cycle, means controlled by said trigger member for rendering said operating means ineffective to operate said thread-gripping means while said trigger member is in holding position during an even cycle of the loom, and means whereby said slide rod is moved inwardly as said laybeam is moved backwardly and said slide rod is moved outwardly as said laybeam is moved forwardly during each cycle of the loom.

4. In a loom having mechanism for reciprocating a laybeam, the combination comprising a laybeam, a pilot-projecting device on said laybeam, said device including a pilot box and a spring-actuated member for projecting a pilot from said box, tripping means including a trigger member for holding and releasing said spring-actuated member, means for engaging and positioning a thread for pick-up by a pilot, means adapted to restrain movement of said thread-positioning means, means connecting between said movement-restraining means and said trigger member whereby said movement-restraining means prevents said thread-positioning means from positioning a thread for pick-up by the pilot whenever said trigger member is in cocked position, and mechanism controlled by the movement of the laybeam for actuating said tripping means to successively bring about interdependent actions of said thread-positioning means to position the thread for pick-up by the pilot and the release of said spring-actuated member to project the pilot.

5. In a loom having mechanism for reciprocating a laybeam, the combination comprising a laybeam, a pilot-projecting device on said laybeam, said device including a pilot box and means for projecting a pilot from said box, means for laterally positioning a portion of a thread disposed across said box toward a pilot in said box for pickup thereby, said thread-positioning means comprising a pivotal arm biased to engage and move the thread toward the pilot in said box, displaceable means adapted to restrain said arm from engaging and moving said thread, said displaceable means including a rockshaft and

a member mounted thereon, trigger means adapted to hold said projecting device in cocked condition, means controlled by said trigger means for displacing said rock-shaft and said member to permit said thread-positioning arm to engage a thread and move the engaged thread into position for pick-up by a pilot in said box, and means for releasing said trigger means from cocked condition.

6. In a loom having mechanism for reciprocating a laybeam, the combination comprising a laybeam, a pilot-projecting device on said laybeam, said device including a pilot box and a spring-actuated member for projecting a pilot from said box, a trigger member for releasing said spring-actuated member to project a pilot, means for disposing a thread across said pilot box, means for laterally moving a portion of the thread toward a pilot in said box for pick-up thereby, said thread-positioning means including a pivoted arm adapted to engage the thread disposed across said pilot box, means adapted to restrain said arm from engaging said thread, means actuated by said trigger member for moving said restraining means from a restraining position to a position wherein said thread-positioning arm is free to engage said thread, means for retracting said thread-positioning arm from thread-engaging position, mechanism for actuating said trigger member and said arm-retracting means, and means operated in unison with the movement of said laybeam for actuating said mechanism.

7. In a loom having mechanism for reciprocating a laybeam, the combination comprising a laybeam, a pilot-projecting device on said laybeam, said device including a pilot box and a spring-actuated member for projecting a pilot from said box, a trigger member, means controlled by said trigger member for holding and releasing said spring-actuated member to project the pilot, means for positioning a thread for pick-up by a pilot, means for restraining movement of said thread-positioning means, said restraining means being movable from restraining position to another position for permitting thread-positioning action of said thread-positioning means, said restraining means including a rockshaft, means connecting between said rockshaft and said trigger member whereby a tripping movement of said trigger member moves said restraining means from restraining position, a bell crank lever having a camming arrangement operable in conjunction with said thread-positioning means to withdraw said thread-positioning means from thread-positioning position, and means adapted to trip said trigger-member to effect the release of said spring-actuated member for projecting a pilot and to actuate said bell crank to effect withdrawal of said thread-positioning means from thread-positioning position.

8. In a loom having mechanism for reciprocating a laybeam, the combination comprising a laybeam, a pilot-projecting device on said laybeam, said device including a pilot box and means for projecting a pilot from said box, said projecting means comprising a plunger, a lever having an arm engaging said plunger and a spring connected to another arm of said lever; means for holding said lever in cocked condition against the tension of said spring, said holding means comprising a pivoted device engaging said lever, a trigger member for controlling the release of said holding means, and means for actuating said trigger member to release said holding means and said pilot-projecting means.

9. In a loom having mechanism for reciprocating a laybeam, the combination comprising a laybeam, a pilot-projecting device on said laybeam, said device including a pilot box and a spring-actuated member for projecting a pilot from said box, means for holding and releasing said spring-actuated member to project the pilot, said means comprising a trigger member and a latching device for said spring-actuated member, means for actuating said trigger member, said actuating means including a

lost-motion connection with said trigger member, a filling thread tensioning device controlled by said actuating means, and means for operating said actuating means.

10. In a loom having mechanism for reciprocating a laybeam, the combination comprising a laybeam, a pilot-projecting device on said laybeam, said device including a pilot box and a spring-actuated member for projecting a pilot from said box, latching means for holding said spring-actuated member in cocked condition, a brake device engageable with and disengageable from a filling thread, a pivoted member connected to said brake device for controlling the operation of said device, a trigger member releasably engageable with said latching means, a lost-motion connection between said trigger member and said pivoted member whereby said brake device is actuated to effect disengagement of the filling thread in advance of the release of said latching means upon movement of said trigger member, and means for actuating said trigger member.

20 11. In a loom having mechanism for reciprocating a laybeam, the combination comprising a laybeam, a pilot-projecting device on said laybeam, said device including a pilot box and a spring-actuated member for projecting a pilot from said box, means for holding said member, said holding means including a trigger, means controlled by said trigger for placing a thread in position for pick-up by a pilot, means for applying tension to a thread being carried by a pilot travelling from said projecting device, means controlled by said trigger for setting said thread-tensioning mechanism to apply tension to a thread carried by a projected pilot, and mechanism controlled by the movement of the laybeam for actuating said trigger whereby to effect successively the positioning of a thread for pick-up by a pilot, the release of said spring-actuated member to project the pilot, and the application of tension to the thread picked up and carried by the pilot.

30 12. In a loom having mechanism for reciprocating a laybeam, the combination comprising a laybeam, a pilot-projecting device on said laybeam, said device including a pilot box and a spring-actuated member for projecting a pilot from said box, a trigger, means controlled by said trigger for holding and releasing said spring-actuated member to project the pilot, clamping means comprising a pair of relatively movable members adapted to receive a thread therebetween when separated from one another and to clamp the thread therebetween when adjacent one another, means for intermittently operating said movable members into adjacent relationship for clamping a thread and into separated relationship, means connecting between said operating means and said trigger, means for moving said trigger in one direction to effect the projection of a pilot from said projecting device and the separation of said members, and means for moving said trigger in the opposite direction to effect cocking of said trigger and a clamping movement of said clamping means.

40 13. In a loom having mechanism for reciprocating a laybeam, the combination comprising a laybeam, a pilot-projecting device on said laybeam, said device including a pilot box and a spring-actuated member for projecting a pilot from said box, a trigger means controlled by said trigger for holding and releasing said spring-actuated member to project the pilot, clamping means for engaging and holding a filling thread which has been inserted by a pilot projected from said device, means for actuating said clamping means, said actuating means including a rockshaft and a yoke member having an arm for actuating said clamping means to clamp a thread and a second arm for actuating said clamping means to open position, means for cocking said trigger, means for tripping said trigger, and means connecting between said rockshaft and said trigger whereby upon movement of said trigger in one direction, said rockshaft and yoke are moved to actuate said clamping means to engage and hold a thread and upon reverse movement of said trigger, said rockshaft and yoke move to open said clamping means.

50 79

14. In a loom having mechanism for reciprocating a laybeam, the combination comprising a laybeam, a pilot-projecting device on said laybeam, said device including a pilot box and a spring-actuated member for projecting a pilot from said box, a trigger means controlled by said trigger for holding and releasing said spring-actuated member to project the pilot, shearing means for cutting a filling thread which has been inserted by a pilot projected from said device, means adapted to hold said shearing means either in an open position to receive a thread or in a closed position, means controlled by said trigger for intermittently actuating said shearing means to close on a thread and to open, means for actuating said trigger to effect the projection of a pilot from said projecting device and the opening of said shearing means, and means for moving said trigger to cock said trigger and effect a closing movement of said shearing means.

15. In a loom having mechanism for reciprocating a laybeam, the combination comprising a laybeam, a pilot-projecting device on said laybeam, said device including a pilot box and a spring-actuated member for projecting a pilot from said box, a trigger, means controlled by said trigger for holding and releasing said spring-actuated member to project the pilot, shearing means for cutting a filling thread which has been inserted by a pilot projected from said device, said shearing means comprising a fixed blade, a spring plate, and a pivoted blade between said fixed blade and said spring plate and arranged to clamp a thread between the pivoted blade and the spring plate as the pivoted blade is moved to cut the thread; means adapted to hold said pivoted blade either in an open position with respect to said fixed blade or in a closed position, means controlled by said trigger for intermittently actuating said pivoted blade to close said shearing means upon movement of said trigger in one direction and to open said shearing means upon movement of said trigger in another direction, said last-named means comprising a rockshaft and members for actuating said pivoted blade in opposite directions, and means connecting between said rockshaft and said trigger whereby movements of said trigger control the closing and opening movements of said shearing means.

16. In a loom having mechanism for reciprocating a laybeam, the combination comprising a laybeam, a pilot-projecting mechanism mounted on said laybeam, said mechanism including a pilot box and a spring-actuated member for projecting a pilot from said box, means for clamping a filling thread until it has been picked up by a pilot projected by said projecting mechanism, said clamping means comprising a pair of relatively movable members adapted to receive a thread therebetween when separated from one another and to clamp the thread when adjacent one another, and means for actuating said projecting mechanism to effect the projection of a pilot from said box, said last-named means including a slide rod and a slide member having a camming pin-and-slot connection therebetween which controls the movement of said

slide member with respect to said slide rod to effect the opening of aid clamping mean, said camming pin-and-slot connection construction and arranged to delay the opening of said thread-clamping means until a pilot is projected and has picked up the thread clamped by said clamping means.

17. In a loom having mechanism for reciprocating a laybeam, the combination comprising a laybeam, a pilot-projecting mechanism mounted on said laybeam, said mechanism including a pilot box and a spring-actuated member for projecting a pilot from said box, means for clamping a filling thread until it has been picked up by a pilot projected by said projecting mechanism, said clamping means comprising a pair of relatively movable members adapted to receive a thread therebetween when separated from one another and to clamp the thread when adjacent one another, means for releasing said spring-actuated member from an initial position to project the pilot, a yoke for opening and closing said clamping means, means controlled by said releasing means for operating said yoke, means for actuating said releasing means to release said spring-actuated member to project a pilot, said last-named means including a slide rod and a slide member having a camming pin-and-slot cam connection therebetween so constructed and arranged to effect the opening of said thread-clamping means after said releasing means has released said spring-actuated member to project the pilot, and means for restoring said releasing means and said spring-actuated member to their initial positions, said last-named means also operating said yoke to close said clamping means.

18. In a loom having mechanism for reciprocating a laybeam, the combination comprising a laybeam, a pilot-projecting device on said laybeam, said device including a pilot box and a spring-actuated member for projecting a pilot from said box, a pilot contained in said box, said pilot having thread-gripping means adjacent each end of said pilot, each of said thread-gripping means comprising a hook secured to said pilot and having an open end pointing away from the end of said pilot closest to the hook, and a plate engaging the underside of said hook, means for positioning a thread in advance of the open end of one of said gripping means for engagement between the hook and plate thereof, said thread-positioning means comprising a pivoted member having a pair of spaced-apart blades adapted to pass along at either side of said hooking element as the pilot is projected from said box, and means for moving said member toward said pilot to position a thread in advance of said hook for pick-up.

UNITED STATES PATENT OFFICE
CERTIFICATION OF CORRECTION

Patent No. 2,971,540

February 14, 1961

George W. Dunham

It is hereby certified that error appears in the above numbered patent requiring correction and that the said Letters Patent should read as corrected below.

Column 1, lines 69 and 70, for "correspondingly" read
-- corresponding --; column 7, line 59, for "thread-breaking"
read -- thread-braking --; column 16, line 60, and column 17,
line 5, after "trigger", each occurrence, insert a comma;
column 18, line 2, for "aid" read -- said --; line 3, for
"construction" read -- constructed --; same column 18, line
50, after "pick-up" insert -- by said hook --.

Signed and sealed this 15th day of August 1961.
